UNITED STATES PATENT OFFICE.

ADOLPHE TANGUAY, OF PETIT BOIS, LONGUEUIL, AND DOMINA QUINTAL, OF MONTREAL, QUEBEC, CANADA.

SWITCH-OPERATING MECHANISM.

1,185,554.

Specification of Letters Patent. Patented May 30, 1916.

Application filed November 26, 1915. Serial No. 63,467.

To all whom it may concern:

Be it known that we, ADOLPHE TANGUAY and DOMINA QUINTAL, both subjects of the King of Great Britain, and residing on 5 St. Pierre street, Petit Bois, Longueuil, and at 2819 St. Dominique street, Montreal, respectively, in the Province of Quebec, Canada, have invented certain new and useful Improvements in Switch-Operating Mechanism; and we do hereby declare that the following is a full, clear, and exact description of the same.

The present invention relates to improvements in a "switch operating mechanism".

15 The main objects of the invention are to provide a simple, efficient, durable, compact and economical switch mechanism, which may be operated automatically in either direction by a car approaching along the main line from 20 either side.

The other objects will appear from the detailed description and claims.

In order to more clearly disclose the construction, operation and use of the invention, 25 reference should be made to the accompanying drawings forming part of this application. It is to be clearly remembered that the drawings are merely an illustration of the invention and show only one preferred 30 form.

In the drawings, Figure 1 is a top plan view of the device with the switch table partly in section. Fig. 2 is a side elevation of the device, showing a car truck and the 35 switch operating member carried thereby. Fig. 3 is a cross section through the switch table, looking to the right of the drawing. Fig. 4 is an enlarged vertical cross-section on line A—A. Fig. 5 is an enlarged vertical cross-section on line B—B. Fig. 6 is an enlarged plan view of the switch table.

Like numerals of reference indicate corresponding parts in each figure.

With reference to the drawings, 1 indicates a suitable casing either formed integrally with or formed separately from and then secured to a rail section. The rail section and casing together make a long narrow box, U-shaped in cross-section and adapted 50 to contain parts of the mechanism. Midway of its length, the casing is enlarged to form a cylindrical well 2 of a much larger diameter. This well is provided with a plurality of horizontal brackets 3 or supports on 55 which may be supported, if desired, anti-

friction rollers, not shown in the drawings. Within the well 2 is rotatably mounted, a switch table 4, said table being centrally provided with a pivot 5 which engages a corresponding recess provided in the center 60 support 6. Thus the table is adequately supported, while at the same time being free to rotate with the least possible friction. The top surface of the table is provided with divergent rail sections, or has formed therein 65 wheel grooves to receive and support the car wheels, which have somewhat the shape of the letter K. In the drawing grooves are shown. One of these wheel grooves extends completely across the table top, while the 70 other two converge about toward the center of the table and there intersects the transversal groove. So by rotating the table, as will hereinafter appear, the main line rail section may be brought into alignment with 75 the main line groove of the table, while at the same time swinging the switch line wheel groove out of line with its rail and vice-versa.

7 is a main shaft suitably journaled within the casing 1 and longitudinally disposed therein, said shaft passing under the switch table and provided at each end with pinions 8 and 9, which co-act with vertically disposed beveled pinions 10 and 11, said pinions 10 and 11 being mounted on stub-shafts 12 and 13 respectively. The upper end of each of said shafts 12 and 13 is provided with a four pointed star wheel 14, in the form of a cross, the points being adapted 80 to pass into and through a recess in the adjacent rail face in a position to be engaged by a trip carried by the car truck. This trip will be fully described hereinafter and it is thought that before describing it, it is preferable to give a thorough description of the 85 switch mechanism.

15 are cams mounted on the shaft 7 preferably two in number and 16 are cams secured to the under side of the switch table, 100 immediately above the cams 15, each bracket having two downwardly depending guide rods 17 and 18 which engage the cam 15. It will, therefore, be easily understood that on turning the star wheel 14, it will cause 105 the beveled gears to rotate, which in turn will rotate the shaft 7 and the cam 15, thereby swinging the switch table into the necessary position. In order to hold the switch table against accidental movement, an ad- 110

justment has been provided below the surface of said table, which consists of a double cam or roller 19 mounted on said shaft 7, and provided with two oppositely disposed 5 notches which are adapted to be engaged by the pin 20 disposed at right angle to said roller, and held in continual contact with said roller or double cam by the spring 21, said pin being preferably secured within 10 the central support on which rests the turn table. It will be seen also that the notches in roller 19 are shaped so that the rod 7 is locked against rotation in one direction.

The trip here shown in the drawings and 15 carried by the car truck, comprises a rod or arm 22, pivotally secured intermediate thereof to the truck frame, preferably on the outer side, and slightly bent at one end and provided with two branches 23 and 24 20 adapted to successively engage two arms in the star wheel 14 and cause a two-quarter or half rotation. 25 is a spring secured to said arm 22 at one end and at the other end to the truck frame and 26 is a foot-lever preferably disposed near the motorman and 25 adapted to operate said arm 22 by means of the operating cords 27 and 28, which are secured to said foot-lever 26 and the free end of said arm 22 respectively, and to a lever 30 arrangement 29 secured to a cross-bar in the frame of the car truck.

In the operation of our device, if the car approaches the table from the right as viewed in Figs. 1 and 6 and the motorman 35 wishes to continue on the main line, he need take no steps to actuate the mechanism, since the table is set so that the car will continue on the main line. If, however, the motorman wishes to turn from the main line 40 into the switch line, he will simply lower the trip which shall grip the star wheel causing the same to rotate, thereby rotating the shaft 7 and swinging the table into the position shown in dotted lines in Fig. 1. If 45 now the motorman approaches the switch along the main line from the left as viewed in Figs. 1 and 6 and finds the table in the position shown in dotted lines in Fig. 1, then he lowers his trip to revolve the table back 50 into the position shown in full lines in Figs. 1 and 6 in a manner similar to that just mentioned.

In case, of course, the table is in the position shown in full lines in Figs. 1 and 6, the 55 motorman approaching along the main line from the left as viewed in Figs. 1 and 6 will not operate the switch mechanism but will run through the switch without changing the same.

60 In case a car approaches the switch along the switch line and the switch is in the position shown in full lines in Figs. 1 and 6, the car proceeds through the switch without pause or without need for changing the 65 switch. In case, however, the car ap-

proaches the switch along the switch line and finds the same in the position shown in dotted lines in Fig. 1, then the motorman will need to stop the car in order to have the same changed before he can proceed onto 70 the main line, since no star wheel is provided, or other means, whereby the switch table may be shifted by the car on the switch line. However, it is believed to be obvious to those skilled in the art, in view of 75 our previous disclosure herein, to arrange the apparatus so that it may be operated also by a car on the switch line.

It is obvious that changes may be made in the construction, arrangement and dispositions of the different parts of the invention and it is meant to include all such in this application, in which only a preferred form 80 has been disclosed.

What we claim is:

1. In a mechanism of the character described, comprising a main line rail, a switch line rail intersecting the same, a switch table rotatably mounted at the point of intersection, and provided with main line and switch 90 line rail sections, a shaft, a cam mounted on said shaft adapted to swing said switch table, means to operate said shaft and means to hold said shaft against accidental movement.

2. In a mechanism of the character described, comprising a main line rail, a switch line rail intersecting the same, a switch table rotatably mounted at the point of intersection, and provided with main line and switch 100 line rail sections, a shaft parallel with said main line rail, a cam mounted on said shaft below said switch table, means provided below said switch table to engage said cam, means to operate said shaft and means to hold 105 said shaft against accidental movement.

3. In a mechanism of the character described, comprising a main line rail, a switch line rail intersecting the same, a switch table rotatably mounted at the point of intersection and provided with main line and switch 110 line rail sections, a shaft suitably journaled and extending below said switch table, a cam mounted on said shaft, guides secured to said switch table engaging said cam, means 115 to operate said shaft and means to hold said shaft against accidental movement.

4. In a mechanism of the character described, comprising a main line rail, a switch line rail intersecting the same, a switch table 120 rotatably mounted at the point of intersection, and provided with main line and switch line rail sections, a main shaft suitably journaled below said switch table, a cam mounted on said main shaft, guides secured to said switch table engaging said cam, a beveled gear mounted on said main shaft, a stub shaft suitably journaled, a beveled gear mounted at the end of said stub shaft co-acting with the gear on said main shaft, 125 130

means to operate said stub shaft and means to hold said main shaft against accidental movement.

5. In a mechanism of the character described, comprising a main line rail, a switch line rail intersecting the same, a switch table rotatably mounted at the point of intersection and provided with main line and switch line rail sections, a main shaft extending below said switch table, cams mounted on said main shaft, guides engaging said cams and adapted to swing said switch table, beveled gears mounted at each end of said main shaft, stub shafts perpendicular to said 15 main shaft, beveled gears mounted on said stub shafts co-acting with the gears on said main shaft, star wheels adapted to actuate said stub shafts and means to hold said main shaft against accidental movement.

6. In a mechanism of the character described, comprising a main line rail, a switch line rail intersecting the same, a switch table rotatably mounted at the point of intersection and provided with main line and switch line rail sections, a shaft, a cam mounted on said shaft adapted to swing said switch table, means to operate said shaft, a roller suitably notched mounted on said shaft, a spring-held pin adapted to engage said notches and hold said shaft against accidental movement. 20 25 30

Signed at Montreal, Quebec, Canada, this 28th day of October 1915.
